UNITED STATES PATENT OFFICE.

RAYMOND L. FOSTER, OF APPONAUG, RHODE ISLAND.

WATER-FEED CONTROL FOR LIQUID-FUEL BURNERS.

Application filed January 2, 1925. Serial No. 180.

This invention relates to improvements in water-feed control-means for liquid-fuel burners employing steam-generating appliances.

5 The principal object of the improvement is to provide means for accurately regulating the amount of water fed to the steam-generating apparatus or vaporizing-chamber to maintain a constant level therein

10 whereby to secure uniform vaporization.

Another object of the improvement is to provide means for reducing the pressure from the water main or supply pipe to eliminate the danger of an unrestricted flow of

15 water liable to flood the burner and quench the flame.

Another object of the improvement is to provide a water-feed control in which the valves are less liable to collect dirt and sediment or to be otherwise hindered from closing to properly fulfill their functions.

Another object of the improvement is to provide a water-supply tank and feed-control device which is more durable in construction and proof against derangement or getting out of order.

Further objects of the improvement are set forth in the following specification which describes a preferred embodiment of

30 the invention as illustrated by the accompanying drawings. In the drawings:

Fig. 1 is a general view of my improved water-supply tank and feed-control device shown as applied to use with a liquid-fuel burner having a steam-generating chamber to which the water feeds;

Fig. 2 is an enlarged plan view of my improved supply-tank and feed-control device; and

40 Fig. 3 a sectional elevation of the same taken on line 3—3 of Fig. 2.

Referring first to Fig. 1 of the drawings, this view illustrates in vertical section a liquid-fuel burner B of the type shown and described in my pending application for U. S. Letters Patent, Serial No. 706,330, filed April 14, 1924. The burner structure comprises in general a concaved fire-bowl 2, from the bottom of which rises a central burner-nozzle 11 surmounted by an air-manifold 3. The burner is embodied in a unitary casting having an outer cylindrical wall 4 formed with a depending bottom flange 5 adapted to rest on the grate G of the furnace F which is here shown in section.

In the burner-nozzle 11 is a central orifice 6 opening from the top of a flaring throat 7 which communicates with a shallow fuel-reservoir or preheating chamber 8 extending laterally beneath the bottom wall of the bowl 2. The fuel-reservoir 8 is bounded by a vertical, cylindrical wall 9 connecting the concaved wall 10 of the bowl 2 with the bottom wall or base 13 of the structure. The vertical wall 9 is spaced inwardly from the outer cylindrical wall 4 of the casting to provide an annular vapor-generating chamber or steam-ring 12 surrounding the fuel-reservoir 8 beneath the bowl 2.

Suitable piping connections 14 lead into the fuel-reservoir 8 from the supply-tank, not herein shown, to supply the burner with liquid fuel. The vapor generated in the steam-chamber 12 passes therefrom into the air-ducts leading up from beneath the grate to the manifold 3, these ducts not being herein illustrated; or in other cases the steam passes down into the ash-pit through one or more vertical pipes 15, and thence is drawn up through the air-ducts to humidify the air supplied through the manifold to the flame. It has been demonstrated that by atomizing the fuel vapor with air carrying a content of water vapor or steam combustion is greatly increased and carbonization practically eliminated. That is to say, the fuel vapor will absorb a higher content of oxygen whereby combustion of the carbon will be more complete and hence the flame will burn with greater intensity to produce a maximum of heat units.

As before stated, the improved burner herein illustrated employs a steam-ring or water-vaporizing chamber 12 to which water is supplied through a suitable pipe 16. The chamber 12 is heated by the flame from the burner impinging against the concaved walls of the fire-bowl 2, and the water in the chamber is maintained constantly at the proper temperature to give off vapor to be conducted through the air-ducts to the flame. It is therefore important that the water be kept at a constant level in the steam-chamber to insure uniform vaporization, and my present improvement is directed to means for regulating the water-feed from the supply-tank to effect this result, while preventing any chance of insufficient feed on the one hand, or flooding the burner on the other.

Referring now to Figs. 2 and 3, my improved water-feed controlling means comprises essentially a partitioned or chambered tank 20 having a main compartment 21 and a smaller pressure-reducing chamber 22. The tank 20 may be of generally rectangular shape and is preferably constructed as a casting to eliminate seams and joints or copper linings, which deteriorate rapidly in use and cause leakage. The preferred type of tank herein illustrated is cast in the form of a box with relatively thin outer walls and an integral inner wall or partition 23 dividing its interior into the main compartment 21 and the pressure-reducing chamber 22. As shown most clearly in Fig. 2, the tank 20 has one side offset at 24 to form the wider, main compartment 21, and the partitioning wall 23 extends longitudinally of its narrower portion with an end-wall 25 forming one boundary of the main compartment 22. At the corners of the main compartment 21 the bottom wall 26 of the casting is thickened to provide bosses 27 having tapped holes 28, into which may be screwed suitable pipes or rods 29 adapted to serve as legs or standards for supporting the tank from the floor.

Another boss 30 at the end of the narrower portion of the tank is tapped to receive a third rod or pipe 31, thus providing a three-point suspension for the tank. The rods or pipes 29 and 31 screw into inverted cups or feet 70 resting on the floor so that the three legs or standards may be adjusted in length by turning the feet thereon to level the tank from the base on which it is supported. By means of this simple and ingenious construction the tank may be leveled very accurately even when supported from rough cement floors such as usually serve for basement settings for furnaces. A cover 32 is usually provided for excluding dirt and dust from the tank 20 and this is preferably constructed as a casting adapted to rest on the top of the tank with lugs 33 engaging the inner rim thereof to hold it in place. Above the main compartment 21 the cover 32 is formed with a dome or swelling 74 to provide clearance space for the ball-float which operates the inlet-valve to be later described.

In the present improved feed-control I employ two float-valves for regulating the water level and pressure in the tank; one as the inlet-valve for the main compartment 21, and the other for controlling the flow from the main compartment to the reducing-chamber 22. Referring to Fig. 2, the longitudinal partition or side wall 23 for the reducing-chamber 22 forms a relatively narrow compartment 34 leading from the main chamber 21, and at its end is the inlet-valve 35. The inlet-valve 35 is of conventional type comprising a tubular valve body stem

screwed down into a thickened boss 36 cast integral with the bottom wall of the tank 20. The boss 36 is drilled clear through and tapped at its lower end to receive the threaded end of a pipe 37 leading from the service pipe supplying water from the city main or other source. In the tubular body stem of the valve 35 is a plunger 38 formed with a tapered lower end 39 adapted to fit the beveled seat 40 on the interior of the stem. The plunger 38 is reduced in diameter throughout a portion of its length and a plurality of ducts 41 are drilled through the sides of the tubular body stem of the valve 35 to provide for the egress of the water therethrough when the plunger is raised off from its seat.

On the side of the stem 35 is an elbow-shaped arm 42 having a forked bearing 43 at the top, between the sides of which is a lever 44 pivoted on a cotter-pin 45. The short end of the lever 44 is provided with a fork or yoke 46 having inwardly projecting studs or pins 47 engaging a peripheral groove 48 at the top of the valve-plunger 38. The opposite arm of the lever 44 is extended in a rod 49 carrying a hollow ball-float 50 at its outer end. As water is admitted through the valve 35 into the main compartment 21 of the tank 20 it will raise the float 50 to depress the plunger 38, and eventually, when the water reaches the prescribed level as indicated in Fig. 3, the plunger will be seated to close the valve to cut off the supply.

The water feeds from the main compartment 21 to the pressure-reducing chamber 22 through a duct or passage 51 cored through a thickened portion of the bottom wall 26 of the tank. Preferably, the duct 51 leads down through a raised boss 52 in the compartment 21, its mouth or opening being elevated above the bottom of the tank so as to be less liable to catch any dirt or sediment collecting therein. A portion of the duct 51 extends horizontally beneath the partition 25 and opens upwardly into the bottom of the reducing-chamber 22 at 53. A drain-hole opens into the duct 51 and is provided with a pipe-plug 54 which may be removed to facilitate cleaning the duct. Screwed into the end 53 of the duct 51 is a tubular valve body stem 55 provided with a sliding plunger 56. The tubular stem 55 is of substantially the same form as the tubular body stem of the valve 35 previously described, except that its throat or inlet opening is preferably slightly larger to permit a faster flow of the water therethrough. The lower beveled end 57 of the plunger 56 fits the tapered seat 58 on the interior of the stem 55 and is held thereagainst by the action of a pivoted lever 59 operated by the ball-float 60 which is lifted as the water rises in the chamber 22. When the level of the

water in the chamber 22 is lowered the float drops and thereby tilts the lever 59 to raise the plunger to unseat its tapered end, whereby the water will have ingress from the valve 5 to the chamber 22 through the ducts 61 in the sides of the stem 55.

The pressure-reducing chamber 22 supplies water to the steam-ring or vaporizing-chamber 12 of the burner B by means of piping connections 62 leading from the corner of the chamber 22 down through the ash-pit door and thence up into the steam-ring through pipe 16 previously referred to, see Fig. 1. Leading from one side of the main chamber 21 of the tank 20 at a distance above the normal level of the water therein is a pipe 65 which may be connected with a drain or trap leading to the sewer. The pipe 65 serves as an overflow drain to carry off the water should the inlet-valve 35 fail to close, due to accident or getting out of order, thus preventing overflow onto the floor of the building in which the apparatus is installed. The method of operation of the complete device is as follows:

The tank 20 is installed in any convenient location at the side of the furnace or boiler F, being supported from the floor by its adjustable legs 29, 31, and elevated at a height to bring the normal level of the water in the pressure-reducing chamber 22 slightly above the bottom of the steam-chamber 12 of the burner B. The tank 20 is leveled by turning the cups or feet 70 on the standards 29 and 31 to adjust their relative length as required for inequalities on the floor on which they rest. The outlet from the pressure-reducing chamber 22 of the tank is connected to the steam-chamber 12 by the piping 62, 16 and the inlet to the main compartment 21 is connected to the service line by piping 66, see Fig. 1, in which is an emergency shut-off valve 67. The valve 67 remains normally open so that water from the city main, or from a gravity tank where city water is not available, will feed into the main chamber 21 of the tank 20 through the inlet-valve 35. The valve 35 is adjusted to permit the chamber 21 to fill to the prescribed level, usually about an inch or two below the top, when the float 50 will be raised to close the valve to shut off the feed. Meanwhile, as the water feeds into the chamber 21 it will flow through the by-pass 51 and valve 55 into the pressure-reducing chamber 22. The valve 55 is adjusted to be closed by the ball-float 60 when the water reaches a level slightly above the bottom of the steam-chamber 12, usually with the chamber 22 approximately one-quarter full. It will thus be seen that while the main chamber 21 is maintained nearly filled with water the chamber 22 will be only one-quarter filled, more or less, so that the pressure therein is greatly reduced, particularly as

the chamber 22 is much smaller than the compartment 21.

It is to be understood that the levels as herein specified and illustrated are merely approximate and may be varied if desired, but in any case the pressure in the reducing-chamber 22 will be much less than that in the main chamber 21. Only a modicum of water is required to generate vapor in the steam-chamber 12 of the burner B, but it is essential that a constant supply be maintained therein at all times to provide for continuous uniform vaporization. Lack of water will prevent steam forming, while an excessive flow will cut down the vaporization, and if continued is liable to flood the burner and quench the flame. With the present improved control-device the water in the steam-chamber is maintained at a uniform level with that in the reducing-chamber 22 of the tank 20 and fluctuations in the pressure from the water-main cannot affect it. That is to say, the reducing-chamber 22 is fed from the main chamber 21 and even though the level may fluctuate somewhat in the larger compartment it will not vary the pressure in the reducing-chamber. This provision for reducing the pressure for the feed to the steam-ring is most important where water is supplied to the tank from high-pressure mains. Abnormal or increasing pressure in the water-main is liable to unseat the inlet-valve 35 and raise the level in the compartment 21, but this will have no effect to increase the pressure in the chamber 22 so that the level remains constant at the point of feed to the steam-ring whereby the level in the steam-ring will always be the same. It is well known that the pressure in city mains varies considerably at different times and under changing demands on the supply, but with the present improved apparatus such fluctuations in pressure cannot affect the feed to the steam-ring which always remains constant and uniform.

As the water in the steam-ring 12 is vaporized and the vapor passed off to the flame the dropping of the level in the chamber 22 will cause the ball-float 60 to open the valve 55 to feed more water from the main compartment 21. Preferably, the valve 55 is balanced to maintain the plunger 56 just off its seat so that a small amount of water bleeds through the valve continuously to maintain the level in the chamber 22 constant without intermittent opening and closing of the valve. In this way the loss from vaporization in the steam-ring is compensated for by a substantially continuous feed so that the temperature of the water in the steam-ring is never lowered appreciably. This provides for a practically constant degree of vaporization in accordance with requirements for effecting the proper humid-

115
120
125
130

ification of the air through the draft-ducts to obtain the maximum efficiency of combustion.

Should the pressure from the main increase abnormally beyond the control of the inlet-valve 35, or should the latter be restrained from closing by foreign substances or dirt, the rising of the water in the compartment 21 will be taken care of at the 10 overflow 65 and no appreciable increase in pressure will appear in the chamber 22. Therefore, the feed to the steam-ring can never remain unchecked to cause flooding of the burner and quenching of the flame. 15 The arrangement of the by-pass or duct 51 is such as to preclude the entrance of foreign particles into the valve 55, most of the dirt and sediment in the water tending to collect in the depressed bottom of the compartment 21, and what little enters the raised opening of the duct is deposited in the bottom thereof, whence it may be readily drained out by removing the plug 54.

It will thus be observed that my invention 25 provides a most efficient and accurate water-feed control for the steam-generating apparatus of the burner for maintaining the water-level therein uniform and the supply constant. The improved apparatus is proof 30 against derangement or getting out of order and operates as a safety-device to prevent flooding the burner and quenching the flame. The improved supply-tank may be conveniently installed and adjusted, is proof against 35 leakage, and much more durable in use than similar devices employed for like purposes.

While I have herein described and illustrated my improved device as applied to a specific purpose, it may also be adapted to a 40 other uses; and likewise, changes may be made in the construction and arrangement of the apparatus without departing from the spirit or scope of the invention.

Without limitation in this respect, I 45 claim:

1. In a feed-control device for feeding water to liquid-fuel burners, the combination of a receptacle having its interior divided into two compartments, a source of water 50 supply, an inlet for admitting the water to the first compartment, means for maintaining the water at a predetermined level in the first compartment, means for feeding the water from the first compartment to the second compartment, means for maintaining the water at a predetermined level in the second compartment, and an outlet leading from the second compartment to feed the water to the burner.

60 2. In a feed-control device for feeding water to liquid-fuel burners, the combination of a receptacle having its interior divided into two compartments, an inlet-valve in one compartment thereof, a source 65 of water supply connected with the inlet-

valve, automatically-controlled means for operating the valve to maintain the water at a predetermined level in said compartment, a by-pass valve for feeding the water from the first compartment into the second compartment, automatically-operated means for operating the by-pass valve to maintain the water at a predetermined level in the second compartment, and an outlet from the second compartment for feeding the water 75 to the burner.

3. In a feed-control device for feeding water to liquid-fuel burners, the combination of a receptacle having its interior divided into larger and smaller compartments, a source of water supply connected to the larger compartment, an inlet-valve for admitting the water to the larger compartment, means for operating the valve to maintain the water at a predetermined level in said compartment, a by-pass valve for feeding the water from the larger compartment into the smaller compartment, means for operating the by-pass valve to maintain the water at a predetermined level in the smaller compartment, and an outlet from the smaller compartment for feeding the water to the burner.

4. In a water-feed controlling device for supplying water at a constant level to liquid-fuel burners, the combination of a one-piece tank having its interior divided into two compartments, a source of water supply connected to the tank, an inlet-valve for admitting water from the supply to one 100 compartment, a float operative to close the inlet-valve when the water reaches a predetermined level, a second valve for admitting water from the first compartment into the second compartment, a float for closing 105 said second valve when the water reaches a predetermined level in the second compartment, and an outlet from the second compartment for feeding water to the burner.

5. A pressure-reducing device and water-feed control for maintaining water at a constant level in the steam-chambers of liquid-fuel burners comprising a one-piece tank having its interior divided into relatively larger and smaller compartments, an 110 inlet-valve in the larger compartment, a source of water supply connected with the inlet-valve, a float for closing said valve when the water rises to a predetermined level in said compartment, a by-pass valve 115 for admitting water from the larger compartment into the smaller compartment, a float for closing the by-pass valve when the water rises to a predetermined level in the smaller compartment, and an outlet leading 120 from the smaller compartment to feed the water to the burner.

6. In a device of the type specified, the combination of a water-supply tank having a vertical partition dividing its interior into 125

two compartments, an inlet-valve in the main compartment, a float for operating said valve to maintain the water at a predetermined level in the main compartment, a by-pass duct leading from a point elevated above the bottom of the main compartment into the second compartment, a valve in said duct, a float for operating said valve to maintain the water at a predetermined level in the second compartment, and an outlet from the second compartment.

7. In a device of the type specified, the combination of a compartmented tank constructed as a casting with integral side walls, bottom and partition, a float-operated inlet-valve in one of the compartments adapted to maintain the water at a predetermined level therein, a duct formed in the bottom of the casting leading from one compartment

ment to the other, a float-operated valve in the duct for maintaining the water at a predetermined level in the second compartment, and an outlet from the second compartment.

8. In a device of the type specified, the combination of a compartmented tank constructed as a casting with integral side walls, bottom and partition, the bottom of the tank being thickened and cored with a duct having its mouth elevated above the bottom of one compartment and leading into the other compartment, a float-operated inlet-valve in the first compartment, a float-operated valve connected to the duct in the other compartment, and an outlet from the second compartment.

In testimony whereof I affix my signature.

RAYMOND L. FOSTER.
